UNITED STATES PATENT OFFICE.

JAMES C. BLAKE, OF PETERSBURG, VIRGINIA.

REFRIGERATOR.

SPECIFICATION forming part of Letters Patent No. 267,770, dated November 21, 1882.

Application filed July 14, 1882. (No model.)

To all whom it may concern:

Be it known that I, JAMES COLEMAN BLAKE, a citizen of the United States, residing at Petersburg, in the county of Dinwiddie and State 5 of Virginia, have invented certain new and useful Improvements in Refrigerators; and I do hereby declare the following to be a full, clear, and exact description of the invention, such as will enable others skilled in the art to which it 10 appertains to make and use the same, reference being had to the accompanying drawings, and to letters or figures of reference marked thereon, which form a part of this specification.

My invention relates to improvements in refrigerators whereby vessels containing liquids 15 may be kept cold, and removed from the cooling-chamber without opening the refrigerator and without admitting the outer air directly to the cooling chamber or chambers proper; 20 and the invention consists in a refrigerator in which are combined an ice-receptacle and a cooling chamber or chambers below said ice-receptacle, and means whereby vessels may be suspended or introduced into the ice-receptacle otherwise than through its door or lid or 25 through the cooling-chamber.

The invention further consists in the means employed for preventing access of atmospheric air in too great a volume to the ice-receptacle 30 through the openings through which vessels are introduced therein, or from which they are suspended when such vessels are removed for use, all as hereinafter fully described, and shown in the accompanying drawings, in 35 which—

Figure 1 is a top plan view of a refrigerator constructed according to my invention, and Figs. 2 and 3 are a vertical longitudinal and a like transverse section, respectively.

Like letters of reference indicate like parts in the above figures of drawings.

C indicates the inclosing-case of the refrigerator, which may be of any desired form and of any usual or preferred construction. It may 45 be arranged into one or more cooling-chambers, c, above which chamber is located the ice-receptacle I, common to all the cooling-chambers where more than one are provided. The top of the refrigerator-casing does not, as 50 is usual, constitute the lid to the ice-receptacle I, but constitutes one of the walls of the refrigerator-case, the ice being introduced into the receptacle through a door, D, closing a suitable aperture in the front wall of the casing.

In the upper wall of the casing C, I form a 55 series of apertures, the number of which will depend, of course, on the size of the refrigerator or the size of the vessels suspended or introduced therein. These apertures a are preferably cylindrical, and are lined with any suitable non-conducting material capable of forming a close joint with a vessel when the latter is placed into it. I may use for this purpose rubber, felt, cloth, or any other analogous material.

The depth of the ice-receptacle will necessarily depend, first, upon the size of the refrigerator, and, second, upon the nature of the vessels placed in the apertures a in the top thereof. When the refrigerator is used for 70 cooling milk the floor of the ice-receptacle should be sufficiently removed from the face of the wall of the casing, so as to permit of the introduction of a milk-can of usual size up to or nearly up to its handles—that is to say, so 75 that the handles of the can will be in proximity to the outer face of the upper wall, w, of the refrigerator-casing C, to permit its withdrawal whenever required. This lining l also serves to hold vessels in position by frictional contact, so that a vessel may be suspended from the apertures a. As the lining l would, however, not prevent the access of air to the ice-receptacle I when the can or other vessel is removed, the apertures may be provided with 80 means for closing them. As, for instance, a disk-valve may be employed, which, when the can is removed, is turned over the aperture to close it. I prefer, however, to use a rubber

disk, D, that has four or more slits, s, radiating from the center toward the periphery of said disk, and of sufficient thickness to cause the lips L, formed by the said slits, to act as springs and maintain their normal position. It is evident that by so slitting a rubber disk 95 it may be passed over a vessel of almost any shape, and yet form a practically-tight joint at the lines of contact, since the lips when depressed, and owing to their elasticity, will lie close to the outer faces of such vessel and form 100

a practically air-tight joint, and when the vessel is removed from the disk the lips will again assume their normal position, and also form practically air-tight joints at their lines of contact, and thus close the aperture over which they are applied. It is also evident that by means of the slotted disks D vessels of a less diameter than the aperture *a* may be inserted into the ice-receptacle, and said aperture be yet practically closed around such vessels.

Instead of a slotted disk, a disk having a central opening, *o*, to fit around a vessel of a given diameter, but of a diameter less than that of the aperture *a*, may be employed. This, however, will necessitate the use of a valve or lid to close the aperture when the vessel is removed, which is not so desirable.

Disks D, having different numbers of slits *s*, or having central openings, *o*, of various diameters, may be used to suit various sizes of vessels V, and said disks may be made removable from around the apertures *a*, which may be accomplished by means of two clamping rings, R R', the former being permanently attached to refrigerator, and the latter being removably connected with the former by means of screws S or otherwise; or any other suitable device for conveniently removing the disks and applying others may be employed. I also prefer to make the peripheral lining *l* of the apertures *a* removable, as it is liable to speedy wear when the vessels held therein are frequently handled, and this may be accomplished in any convenient manner.

By means of this construction of refrigerator access may be had to the contents of the cans or vessels V without disturbing the contents in the cooling chamber or chambers C, and the outer air that enters through the openings *a*, where the slotted disks are dispensed with, passes directly into the ice-receptacle I to force the cooler air into the chamber or chambers below and to be cooled before it can reach said chambers. On the other hand, access may be had to the contents of the cooling chamber or chambers C without disturbing the cans, and the outer air that enters into said

chamber will be cooled before it reaches the cans by passing over the ice in the receptacle I.

Any suitable or usual provision may be made to carry off the waste-water resulting from the melting of the ice.

This construction of refrigerator is especially desirable for preserving articles that are readily tainted by their proximity to other articles— such as butter and milk or meats and milk, &c.

Having now described my invention, I claim—

1. A refrigerator having a series of apertures, *a*, in direct communication with the ice-receptacle, said apertures being provided with a lining, substantially such as described, whereby a vessel may be introduced into the ice-receptacle from without and held suspended therein by frictional contact with the said lining, and whereby an air-tight joint is obtained at the same time between the lining and the vessel, substantially as and for the purposes specified.

2. A refrigerator in which are combined an ice-receptacle, one or more refrigerating-chambers below said ice-receptacle, and apertures communicating with the latter and the exterior of the refrigerator, the flexible disks D, applied to said apertures as described, and substantially as and for the purposes specified.

3. A refrigerator in which are combined an ice-receptacle, one or more cooling-chambers below said ice-receptacle, and apertures communicating with the latter, and the exterior of the refrigerator provided with a yielding or flexible lining, the flexible disks D, removably applied to said apertures, whereby vessels of different diameters may be introduced into the ice-receptacle from without, and an air-tight joint obtained between the vessel and aperture, as and for the purposes specified.

In testimony whereof I affix my signature in presence of two witnesses.

JAMES COLEMAN BLAKE.
